UNITED STATES PATENT OFFICE.

WALTER C. BURRELL, OF CHICAGO, ILLINOIS, ASSIGNOR TO MASONIC HISTORY COMPANY, OF CHICAGO, ILLINOIS.

DESIGN FOR A BOOK COVER.

Application filed August 22, 1925. Serial No. 14,554. Term of patent 14 years.

To all whom it may concern:

Be it known that I, WALTER C. BURRELL, a citizen of the United States, residing at Chicago, in the county of Cook and State of Illinois, have invented a new, original, and ornamental Design for a Book Cover, of which the following is a specification, reference being had to the accompanying drawing, forming part hereof.

The figure is a face view of the design.

I claim:

The ornamental design for a book cover, as shown.

WALTER C. BURRELL.
